B. G. LEFERE

BRAKE

Filed Sept. 21, 1923

Inventor

Benonie G. Lefere
By his Attorneys
Blackmar, Spence & Etch

UNITED STATES PATENT OFFICE.

BENONIE G. LEFÈRE, OF FLINT, MICHIGAN, ASSIGNOR TO GENERAL MOTORS CORPORATION, OF DETROIT, MICHIGAN, A CORPORATION OF DELAWARE.

BRAKE.

Application filed September 21, 1923. Serial No. 664,017.

This invention relates to brakes and is illustrated as embodied in a full wrapping internal band brake arranged on the rear wheel of an automobile.

5 One feature of the invention relates to an improved arrangement of toggle mechanism for brakes of the full wrapping type to permit the use of a pair of bell crank levers for the toggle links, in such a manner as to secure application of the band expanding force in a substantially circumferential direction instead of in a direction having a considerable radial component as with an ordinary toggle. One satisfactory 10 form of the improved toggle mechanism includes bell crank levers connected to the opposite ends of the brake band and jointly connected to an operating device, and a floating rigid fulcrum member on which 15 both of the bell crank levers are pivoted so that the entire toggle mechanism may have a limited circumferential movement with the brake band without disturbing the relative positions of the fulcrums of the bell 20 crank levers.

Other features of the invention relate to an arrangement of a full wrapping brake having a support on the open side of the drum with a stop member such as a bracket 25 mounted on the support and extending between the ends of the brake band to serve as an anchoring abutment for whichever end of the band, according to the direction 30 of movement of the drum, transmits the braking torque to the support; and to a novel band positioning device including a fixed bracket arranged to determine the contracted or idle position of the band and which is slotted to receive an inwardly 35 extending projection on the band to determine 40 its lateral position.

These and other features of the invention, including various novel combinations and desirable particular constructions of parts, 45 will be apparent from the following description of the illustrative embodiment shown in the accompanying drawings, in which:

Figure 1 is a vertical section just inside the road wheel, and with the side of the 50 drum partly broken away, showing various parts of the brake in side elevation; and

Figure 2 is a section on the line 2-2 of Figure 1 showing the mechanism for operating the brake band.

55 In the form selected for illustration the

brake comprises a drum 10 mounted on a road wheel 12 rotatably supported on a rear axle casing 14 on which is fixedly mounted a stationary support 16 carrying a plate 18 closing the open side of drum 10. 60

According to the present invention, an internal full wrapping brake band 20 is arranged inside of drum 10 in such a manner that the braking torque is transmitted by one end or the other of the band, according 65 to which direction the drum is turning, to a bracket 22 having oppositely facing portions extending between the ends of the band and a central portion which is riveted or otherwise secured to the support 16. Both 70 ends of the band are normally held in engagement with the bracket by a spring 24. The band is operated by a brake shaft 26 through suitable driver-controlled connections rocking an arm 28. Shaft 26 carries 75 a pair of rocker arms 30 pivotally connected by a link 32 to two oppositely extending pairs of bell crank levers 34 and 36 connected to opposite ends of brake band 20 at 38 and 40.

As explained above, one important feature of the invention relates to controlling the direction of operation of the toggle levers 34 and 36, in such a manner as to eliminate most of the radial component, by providing 80 a rigid floating fulcrum member such as a curved link 42 pivotally connected to bell crank levers 34 at 44 and to bell crank levers 36 at 46. By this arrangement the entire 85 toggle mechanism is free to have a limited angular movement to permit the necessary circumferential movement of band 20, while at the same time bell crank levers 34 and 36 are so anchored at 44 and 46 that the effective direction of their thrusts is substantially circumferential of band 20, there being practically no radial component of 90 this thrust which tends to force the ends of the band against the drum 10. Thus the band is expanded with substantial uniformity. 95

According to another feature of the invention the idle position of band 20 is determined by brackets 50, three being shown, each of which brackets is riveted or otherwise secured to the stationary plate 18. Each bracket has a segmental portion or flange 52 extending inside of brake band 20 to determine its inner or idle position, and the segmental portion is slotted as shown in 100 11

Figure 1 at 54 slidably to receive an inwardly extending projection 56 riveted or otherwise secured to band 20, in such a manner as to determine the lateral position of 5 the brake band and to prevent the band from rattling.

While one illustrative embodiment of my invention has been described in detail, it is not my intention to limit its scope to that 10 embodiment or otherwise than by the terms of the appended claims.

I claim:

1. A brake comprising, in combination, a drum, an expansible and contractible band 15 having a limited circumferential movement with respect to the drum, stops for opposite ends of the band, a pair of bellcrank levers pivotally connected to the band and to each other to constitute a toggle for operating the band, means operating on the pivotal connection between the bellcrank levers to break and to straighten the toggle, and a floating member 20 pivotally connected to both bellcrank levers and providing fulcrums therefor.

2. A brake comprising, in combination, a drum, an expansible and contractible band having a limited circumferential movement 25

with respect to the drum, stops for opposite ends of the band, a pair of levers pivotally connected to the band and to each other to constitute a toggle for operating the band, means operating on the pivotal connection 30 between the levers to break and to straighten the toggle, and a floating member pivotally connected to both levers at intermediate points and providing fulcrums therefor.

3. A brake comprising, in combination, a drum, an expansible and contractible band having a limited circumferential movement 40 with respect to the drum, stops for opposite ends of the band, a pair of bellcrank levers pivotally connected to the band and to each other to constitute a toggle for operating the band, a driver-controlled rock 45 arm connected to the pivotal connection between the bellcrank levers, and a rigid floating link pivotally connected at opposite ends to the bellcrank levers to provide angularly-shiftable fulcrums therefor.

4. A full-wrapping band brake having a pair of band-expanding bellcrank toggle levers connected by a floating fulcrum link.

In testimony whereof I affix my signature.

BENONIE G. LEFÉRE.
